UNITED STATES PATENT OFFICE.

HARRY A. REULING, OF MATAMORAS, PENNSYLVANIA.

DESIGN FOR A REAR LAMP FOR AUTOMOBILES.

Application filed November 21, 1924. Serial No. 11,440. Term of patent 14 years.

To all whom it may concern:

Be it known that I, HARRY A. REULING, a citizen of the United States, residing at Matamoras, in the county of Pike and State of Pennsylvania, have invented a new, original, and ornamental Design for a Rear Lamp for Automobiles, of which the following is a specification, reference being had to the accompanying drawing, forming part thereof.

The drawing shows—

In Fig. 1 an elevation of the lamp as seen from the rear of an automobile when the lamp is mounted therein; and

In Fig. 2 a side elevation of the lamp.

I claim:

The ornamental design for a rear lamp for automobiles, as shown.

In testimony whereof I affix my signature.

HARRY A. REULING.
